(57) **CLAIM**

The ornamental design for a skateboard training apparatus, as shown and described.

DESCRIPTION

FIG. 1 is a front perspective view of a skateboard training apparatus showing the new design;

FIG. 2 is a front view thereof, the back view being the same image thereof;

FIG. 3 is a right side view thereof, the left side view being the same image thereof;

FIG. 4 is a top view thereof;

FIG. 5 is a bottom view thereof; and,

FIG. 6 is a front perspective view thereof of the design in the context in which it is intended to be used, the dashed lines form no part of the claimed design.
